ATTORNEY

UNITED STATES PATENT OFFICE.

RAYMOND H. SARELL, OF GOLDEN, COLORADO.

KEY-FASTENER.

1,286,424.

Specification of Letters Patent.

Patented Dec. 3, 1918.

Application filed December 5, 1917. Serial No. 205,537.

To all whom it may concern:

Be it known that I, RAYMOND H. SARELL, a citizen of the United States, residing at Golden, in the county of Jefferson and State of Colorado, have invented certain new and useful Improvements in Key-Fasteners, of which the following is a specification.

This invention relates to certain new and useful improvements in key-fasteners and its primary object is to provide a device of very simple construction which is adapted to secure a key inserted in the lock of a door against operative movement or unauthorized removal from either side thereof.

Another object of my invention is to provide a key-fastener of the above described character which is readily applied to a lock and key without marring the door or drawer on which the fastener is used, by the use of screws or other fastening devices and which in its operative position provides a most efficient substitute for Yale locks, bolts, catches and other similar devices often applied to a door as a safe-guard against its being opened by unauthorized persons.

The use of my invention will not only frustrate attempts at "picking" a lock by means of a skeleton key or by turning a key inserted in the lock, by the use of nippers, but it will also prevent the operation of the lock from the inside of a door and thus makes it possible to securely lock a door of a closet, wardrobe or other room used for the storage of clothing and other articles, or to secure a drawer of a desk, dresser or other piece of furniture against being opened by the ordinary method of turning the key within the lock thereof.

My invention is in this respect, particularly valuable for the use of travelers, inasmuch as it provides a portable and readily applied means to prevent access to articles placed in drawers or closets of hotel rooms, during the absence of its occupant.

With the above objects in view my invention consists of the constructions and combinations of devices illustrated in the accompanying drawing, in the various views of which like parts are similarly designated, and in which—

Figure 1 is a face view of a door-lock to which my invention is applied,

Fig. 2, a section through the lock taken along the line 2—2, Fig. 1,

Fig. 3, a horizontal section through the lock, along the line 3—3, Fig. 1,

Fig. 4, a perspective view of the guard comprised in my invention as shown in Figs. 1, 2 and 3, and

Fig. 5, a section similar to that of Fig. 2, illustrating a modification in the construction of my invention.

Referring more specifically to the drawings, the reference numeral 2 designates a door provided with a lock 3, and 4 a key of conventional construction used for the operation of the lock.

My improved fastener comprises a guard 5 which in the preferred form of my invention shown in Figs. 1 to 3, consists of a flat and narrow blade or shank 6 formed integrally with a head 7 which is twisted at right angles to the sides thereof.

The head consists of a U-shaped plate formed by bending a widened extension of the blade 6 upon itself. The substantially parallel spaced parts of the head have aligned apertures 8 to receive the shackle 9 of a padlock 10 and they provide an entrance 12 which faces the shank of the guard for the reception of a bow of a key in a lock to which the guard is applied.

In the use of my invention, a door or drawer is locked as usual, by turning the key in the lock and the key is left in its locked position with its bit 13 and its bow 14 extending at right angles to the keyhole 15 of the door.

With the parts in this position the guard is applied by inserting its flat shank in the keyhole below the key and moving it inwardly until the bow of the key occupies the space between the two parts of its head. The shackle of the padlock is passed through the aligned apertures of the head and the key-bow after which the padlock is locked either by the use of a key, or by snapping its shackle into interlocking engagement with its interior mechanism.

It will be seen that with the parts in this position, an operative movement of the key by turning it in the lock, is impossible while the padlock secures the guard against removal from the key and the lock except by the use of a proper key for the release of a shackle.

It will be understood that the guard may be varied in form and construction to adapt it for use in connection with keys and locks of different kinds, that a locking-means other than a padlock of the construction shown in the drawings may be used to fas-

ten the guard and key together, and that other changes may be availed of within the spirit of my invention as defined in the hereto appended claims.

- 5 In the construction shown in Fig. 5 of the drawings, a lock 16 of the padlock type is permanently connected with the shank 6 of the guard in the place of the head 7 of the first-described form of the invention, 10 and the shackle 17 of the lock passes through the bow of the key after the guard has been inserted in the lock so as to register the same with the opening of the lock 16 into which the bit of the shackle enters for its 15 engagement with the interior mechanism of the same.

Having thus described my invention what I claim and desire to secure by Letters-Patent is:

- 20 1. A key-fastener of the character described comprising a flat shank adapted for insertion in a key-hole, a head composed of an extension of the shank, bent upon itself at right angles to the sides thereof and providing a space to receive the bow of a key 25

inserted in a lock to which the fastener is applied, the spaced parts of the head having apertures to register with the opening of the key-bow, and a key-controlled lock on the head of the fastener, including an adjustable shackle which passes through the apertures of the head for locking the key to the fastener. 30

2. A key-fastener of the character described comprising a flat shank adapted for 35 insertion in a key-hole, a head on said shank having an aperture to register with the bow of a key inserted in a lock to which the fastener is applied, and a key-controlled lock on the head of the fastener, including 40 an adjustable shackle which passes through the aperture of the head for locking the key to the fastener.

In testimony whereof I have affixed my signature in presence of two witnesses.

RAYMOND H. SARELL.
